PAVEMENT JOINT

Alan E. Brickman, Buffalo, N. Y., assignor to Acme Highway Products Corporation, Buffalo, N. Y.

Application June 10, 1952, Serial No. 292,697

5 Claims. (Cl. 94—17)

This invention relates to improvements in pavement joints of the type used to connect adjacent slabs of cement concrete pavements, and particularly to joints of this type which compensate for contraction of such pavements. Portland cement concrete pavements are subject to expansion and contraction due to reactions caused by initial setting, thermal coefficient of expansion, moisture absorption and aging.

Expansion joints in a pavement usually include a compressible filler placed between abutting ends of pavement slabs. The expansion of a pavement compresses this joint filler material without appreciable increase in the stresses in the pavements. Contraction joints on the other hand provide for thermal or other contraction of a pavement, which generally shows up as an opening between the slabs when a cut joint has been provided between slabs, or in one or more cracks when no cut joint has been provided. Due to low tensile strength of cement concrete, relief of contraction stresses is nearly always in the form of crack openings intermediate of the ends of the slabs, which tend to reduce the load-carrying capacity of the pavement.

One of the objects of this invention is to provide a contraction joint of new and improved construction between pavement slabs.

A further object is to provide new and improved load transfer members for use in connection with pavement joints of this type.

It is also an object of this invention to provide a load transfer contraction joint including longitudinally extending plates arranged in vertical and horizontal directions and connected with each other by means of load transfer members.

Another object is to provide load transfer members with means of improved construction for securing the longitudinally extending plates thereto.

Other objects and advantages will be apparent from the following description of some embodiments of the invention, and the novel features will be particularly pointed out hereinafter in connection with the appended claims.

In the accompanying drawings:

Fig. 1 is a fragmentary top plan view of a contraction joint embodying this invention.

Fig. 2 is a fragmentary elevation thereof.

Fig. 3 is a transverse sectional elevation thereof on an enlarged scale on line 3—3, Fig. 1.

Figs. 4 and 5 are respectively horizontal sections on lines 4—4 and 5—5, Fig. 3.

Fig. 6 is a sectional elevation thereof on line 6—6, Fig. 3.

Fig. 7 is a side elevation of a load transfer member as originally formed by casting.

The drawings illustrate by way of example one embodiment of this invention, and in these drawings are shown load transfer members designated generally at 10. These load transfer members are mounted on the plane of weakness plate 11, which is supported by the load

2

transfer members in a substantially upright plane, and a base plate 12 is secured to the lower parts of the load transfer members. The two plates may be made of any substantially rigid material, relatively thin steel being preferably employed.

The load transfer members each include a base portion 15 which has a flat, lower face formed to rest on the sub-grade of pavement. This base member may be of any suitable or desired shape, that shown being substantially segmental in cross section and provided with a curved upper surface 16. The load transfer member also includes a pair of upright parts 17 formed integral with the base 15 and spaced apart in positions to receive between them the upright plane of weakness plate 11. The upper ends of these upright parts 17 terminate in substantially horizontal, extending anchor members 18 which extend in spaced relation above the base member 15 and are to be embedded in adjacent slabs of concrete. These anchor members may terminate in enlarged ends 19 which serve to cause the anchoring members to become more securely bonded to the concrete slabs. The anchoring members may be of any other suitable or desired form, and the upright parts 17 are preferably provided with substantially flat surfaces formed to bear against the plane of weakness plate 11.

In order to ensure the desired positioning of the load transfer members lengthwise of the upright plate 11, this plate is provided at intervals lengthwise thereof with suitable means for locating the load transfer members 30 thereon, such for example as notches or recesses 21 extending into the plate from an edge thereof, and at least one of the upright parts 17 is provided with a boss or projection 22 of approximately the same shape as the notches 21, and extending into the space between the 35 two parts 17. Consequently, when the upright parts 17 are in the positions shown in Fig. 3 and the upright plate 11 is correctly inserted between the upright parts 17, the notches 21 in this plate will cooperate with the projections 22 in such a manner that the projections extend into 40 the notches.

At least one of the upright parts 17 is also provided near the upper end thereof with a tooth or projection 24 which, as shown in Fig. 3, extends partly across the space between the two upright parts 17. Since these upright 45 parts are somewhat flexible, the upright plate 11 may be forced past the tooth or projection 24, and thus passed into the space between the two upright parts 17. To facilitate the insertion of a plate between the upright parts 17, each tooth or projection 24 may also be provided with an upper, inclined or bevelled face 25. Consequently, the projecting parts 22 serve not only to locate the load transfer members lengthwise of the upright plate 11, but also limit the extent to which this plate may be moved downwardly relative to a load transfer member, and the tooth 50 24 serves to prevent the load transfer member from moving downwardly relatively to the upright plate 11 so that the load transfer members are held in fixed positions to the upright plate 11. Any other suitable means for correctly positioning the load transfer members on the upright plate 11 may be provided.

In order to facilitate the production of the load transfer members during molding, these members are preferably molded into the form shown in Fig. 7, with the upright parts 17 diverging upwardly from the base 15. Since 55 these load transfer members are preferably made of malleable castings, the upright parts 17 can readily be bent toward each other after removal of the same from the molds to lie in substantially parallel relation, as shown in Fig. 3. Malleable metal also has limited resilient properties giving 60 flexibility of springiness to the upright parts as heretofore stated. By casting the upright parts as shown in Fig. 7, the space between the upright parts, after they are bent

into substantially parallel relation to each other, may be very small, just sufficient to receive a relatively thin steel plate, and by casting the load transfer devices in this manner, expensive coring is avoided and the filing, grinding and inspection of the inner faces of the upright parts is facilitated. This manner of casting the load transfer devices also makes it possible to easily form the boss or projection 22 on the inner face of an upright part 17. By spacing the upright parts 17 closely together, the load transfer devices have a higher load transfer value as compared with similar constructions of equal cross section in which the upright parts 17 are spaced farther apart.

A base plate 12 may be secured to the load transfer member in any suitable or desired manner. In the construction illustrated by way of example, the base portion 15 of each load transfer member is provided on the lower face thereof with a recess 27 of such size and shape that the base plate 12 may readily fit into the same. The base of the load transfer member is also provided with a downwardly extending, short stud 28, preferably formed integral therewith, and the base plate is provided at intervals with holes or openings through which the studs 28 of the load transfer members may be inserted. These studs, after passing through the holes in the base plate, may then be riveted or burred over so that the base plate will be firmly secured to the load transfer members.

In order to facilitate the assembly of the load transfer members and the plates 11 and 12, the plate 11 is preferably temporarily held in inverted position. The load transfer members are then pushed downwardly into correct relation to the notches 21 until the teeth 24 snap across the opposite edge of the plate 11. The base plate is then placed into position to enter the recess 27 in the bases of the load transfer devices with the studs 28 passing through the holes in the base plate, whereupon the outer ends of the studs may be riveted or burred over to secure the bottom plate in place.

When the load transfer members are secured to the upright plate 11 and the base plate 12, an assembled unit is formed which is then ready to be placed on the subgrade of a pavement without requiring any further work thereon. The construction of the joint connection described has the advantage that the assembled units have the two plates 11 and 12 arranged in T-formation so that the assembled units can be readily handled for shipping and positioning on the subgrade and will not readily flex or bend in any direction.

In order to support this unit in correct position and prevent displacement of the same when the cement concrete is poured, the base plate is preferably provided at intervals with holes 30, Fig. 1, through which spikes or stakes 31, Fig. 2, may pass. These stakes are then driven into the subgrade. Preferably the holes 30 are alternately arranged at opposite sides of the center of the base plate 12 and the stakes 31 are preferably long enough to extend upwardly from the base plate after being driven into the subgrade along opposite sides of the upright plate 11, so that this plate will be held in correct position by these stakes as well as by the bases of the load transfer members.

In the use of these contraction joints, the assembled units, including the load transfer members, the upright plates 11 and the base plates 12, are properly positioned on the prepared subgrade between the usual road forms 29, Figs. 1 and 2, and secured in place on the subgrade by means of the stakes 31. The wet cement concrete is then poured between the forms over and around the assembled units in an amount sufficient to screeding or leveling off to a level slightly above the upper ends of the load transfer members, whereupon the usual reinforcing bars 32 are placed on the screeded top surface of the cement concrete. Additional cement concrete is then poured to complete the slabs. Before the last mass of wet cement concrete is poured, locating pins 33 are applied to the ends of the upright plates 11 in such manner that the

upper ends thereof will be at or slightly above the final upper surface of the pavement. These locating pins may be of any suitable construction, those shown being in the form of plates bent into substantially U-shaped cross sectional form so that they may grip or clamp themselves to the ends of the upright plates 11. These locating pins are desirable for the reason that they serve to indicate the position of the joint member, and particularly of the upright plate 11 when the same is covered with concrete. At the prescribed time, after finishing the upper surface of the pavement, a plane of weakness groove or recess 35 is cut into the pavement on a line between the opposite locating pins 33 so that this recess will be located directly above the upright plate 11. This groove or recess is subsequently filled with an elastic sealing material, such as commonly used to exclude infiltration of water and foreign material.

In the operation of the contraction joint, if the pavement slabs contract to a sufficient extent, then because of the low tensile strength of cement concrete, cracking of the pavement will occur, and these cracks, because of the plane of weakness plate 11 and the groove 35, will occur in the space between this plate and the groove and in a substantially vertical plane at one or both sides of the upright plate 11. Cement concrete will not adhere with much tenacity to metal surfaces of the plates or load transfer members and, consequently, the crack in the pavement may readily separate one or both slabs from the upright plate 11. There is only a relatively small, vertical space between the groove 35 and the plane of weakness plate 11, and another small space of this type exists below the plane of weakness plate. Consequently, the cement concrete pavement has the minimum resistance to cracking in approximately the plane of the plate 11, and when a crack occurs in the pavement slab along the groove 35 will merely be stretched and thus continue to keep moisture and foreign material out of the crack. The base plate 12 serves a similar purpose of preventing such foreign material from entering into the part of the crack below the upright plate 11. When these cracks occur in the pavement at the juncture of two adjacent slabs, no damage to the pavement will result, and the load transfer members will keep the adjacent edges of the two slabs in alinement and prevent damage to the pavement. These load transfer means or devices provide for surface alinement of adjacent ends of slabs at a joint and are of designed strength and principal as necessary to maintain this alinement under the stresses applied by passing wheel loads over the joint, and internal stresses of the concrete. When the pavement contracts sufficiently to form cracks between adjacent slabs, the slabs will move away from the ends of the base 15 and from the lower portions of the upright parts 17. Since the anchor members 18 are embedded in the opposite slabs, the separation of the slabs will cause the upright parts 17 to bend or flex to a slight extent relatively to the base 15, but this flexing is very slight and will not result in breaking of the upright parts. The anchor members cooperating with the bases 15 of the load transfer devices will hold the adjacent ends of the pavement in alinement and will transfer wheel loads from one pavement slab to an adjacent one. It will be understood that various changes in the details, materials and arrangements of parts which have been herein described and illustrated in order to explain the nature of the invention may be made by those skilled in the art within the principle and scope of the invention as expressed in the appended claims.

I claim:

1. A pavement contraction joint comprising a plurality of load transfer members each having a base, a pair of flexible upright parts formed integral with said base and in closely spaced relation to each other, anchor members extending outwardly in opposite directions from the upper ends of said upright parts and integral therewith, a tooth

on one of said upright parts extending into proximity to the other upright part, an elongate upright plate carried by said load transfer members, said upright plate having a minimum thickness greater than the minimum distance between the outer portions of said tooth and 5 said other upright part, whereby said upright plate is snap held by said upright parts upon being passed between the upper ends of said upright parts, and past said tooth, and means for locating said load transfer members in spaced relationship to each other along said upright plate.

2. A pavement contraction joint as in claim 1, and wherein said locating means comprises a notch on said upright plate, and a projection on the inside of one of 10 said upright parts extending toward the other of said upright parts cooperating with said notch.

3. A pavement contraction joint as in claim 1, and having a horizontal plate underlying said upright plate and secured to the bases of said load transfer members.

4. A pavement joint as in claim 1, said bases of said load transfer members being recessed, a horizontal plate underlying said upright plate and seated in said recesses and secured to said bases, and wherein said locating means comprises a notch on said upright plate, a projection on 25 the inside of one of said upright parts extending toward the other of said upright parts cooperating with said notch, said projection being arranged in vertical alignment with said tooth.

5. A load transfer member of malleable metal for pavement contraction joints comprising a base, the bottom of said base being recessed for receipt of a flat horizontal plate, a stud in said recess for locking said hori- 30

zontal plate in position, a pair of flexible upright parts formed integral with said base and in closely spaced relation to each other, anchor members extending outwardly in opposite directions from the upper ends of said upright parts and integral therewith, a projection spaced above said base on the inside of said upright parts and extending toward the other of said upright parts for cooperation with a notch in an elongated upright plate thereby locating said load transfer member on said elongated upright plate, a second projection on the upper end of one of said upright parts above said first mentioned projection extending toward the upper end of the other of said upright parts, said first and second projections providing locking means, whereby an elongated upright plate when inserted between said second projection on the one of said upright parts and the inside upper end of the other of said upright parts, causes said upright parts to flex away from each other until said upright plate clears said second projection whereupon said upright parts snap back to lock said upright plate in position.
